CLAIM

The ornamental design for a charging post for a floor washing appliance, as shown and described.

DESCRIPTION

1.1 is a front view showing a first charging post for a floor washing appliance;

1.2 is a back view thereof;

1.3 is a left view thereof;

1.4 is a right view thereof;

1.5 is a top view thereof;

1.6 is a bottom view thereof;

1.7 is a front, left perspective view thereof;

1.8 is a back, top perspective view thereof;

1.9 is a front, bottom perspective view thereof;

2.1 is a front view showing a second charging post for a floor washing appliance;

2.2 is a back view thereof;

2.3 is a left view thereof;

2.4 is a right view thereof;

2.5 is a top view thereof;

2.6 is a bottom view thereof;

2.7 is a front, left perspective view thereof;

2.8 is a back, top perspective view thereof; and

2.9 is a front, bottom perspective view thereof.

(Continued)

The broken lines in the reproductions depict portions of the charging post for a floor washing appliance that form no part of the claimed design.
